COIN TESTER

William Patzer and Walter A. Tratsch,
Chicago, Ill.

Application July 27, 1940, Serial No. 347,933

3 Claims. (Cl. 194—100)

This invention relates to coin testing devices and has as its principal object the provision of coin testing means which employs the coin to generate an electro-motive force by passage between the pole pieces of an electromotive generator, the force thus developed being employed to actuate certain selecting mechanism.

Viewed from another aspect, the invention provides a coin testing device including a chute having acceptance and exit openings and an electromotive generator including spaced metallic poles in the chute between which the coin is pushed in frictional engagement with the poles to generate a force, the magnitude of which is dependent upon the physical characteristics of the coin.

A further object is the arrangement of at least one of the poles to yield to permit introduction of the coin between the poles and yet maintain a firm frictional pressure on the coin during its transit therebetween.

A further object is the provision of an electro-sensitive device in the nature of a galvanometer type relay to be actuated by a current of certain magnitude from an electro-motive force generated by certain coins to operate selecting means for directing the coins variously toward the acceptance and reject exits.

Still another object is the provision in a coin testing device of the class described including an electromotive generator, of electrically operated coin selecting means operated by current from a source other than the couple, and an electro-sensitive device or galvanometer type relay actuated by the couple for connecting the electrically operated selecting means with said other source, together with connections through the galvanometer relay providing a temporary locking circuit to hold up the electrically operated selecting means and give a coin time to pass into the proper exit.

A further object is the provision of manually operated means for pushing the coin through the electromotive generator and also to operate a switch to break an auxiliary work circuit for the testing means, which switch controls such auxiliary work circuit through the galvanometer relay and electrically operated selecting means after the coin has had time to pass the selecting means.

A still further object is the arrangement of the electromotive couple to operate as a diameter gauge for the coin.

Yet another object is the arrangement of the electromotive generator to engage the peripheral

edge portions or rim of the coin to avoid defacement of the profile of the coin.

Other objects, advantages and novel aspects of the invention reside in certain details of construction as well as the cooperative relationship of the component parts of the illustrative embodiment described hereinafter in view of the annexed drawings, in which:

Fig. 1 is a front perspective of the testing unit;

Fig. 2 is an enlarged rear perspective of the testing unit;

Fig. 3 is a transverse vertical section through the unit;

Fig. 3a is a vertical sectional detail view taken along line 3a—3a in Fig. 2;

Fig. 4 is a longitudinal vertical section looking in the direction of lines 4—4 of Fig. 3;

Fig. 5 is a fragmentary interior perspective showing the electromotive couple and coin pusher;

Fig. 6 is a circuit diagram.

The testing unit shown in Fig. 1 comprises a thin chute member adapted for mounting in an upright position on some associated apparatus to be controlled, the chute being constructed preferably of an insulating material, such as fiber, in a front wall plate 10 of which is a coin entrance 11 communicating to an interior chute passage to be described in view of Fig. 4. An operating handle 12 projects from the lower portion of the chute and is journaled in a bushing 13 (Fig. 3) with a shaft portion 15 extending from the rear face plate 16 of the chute, as shown in Fig. 2, for connection with a mounting hub 14 from which extends a pusher operating arm 15a.

The body of the chute preferably includes an intermediate cut-out plate 17 (Figs. 3 and 4) which is clamped between the front face plate 10 and the rear face plate 16, suitable screws 18 holding the plates together, the intermediate cut-out plate 17 also including a section 17a which provides a descending runway portion 19 leading into a reject exit 20 opening into the bottom edge 45 of the chute. The opposite side of the section 17a is spaced from the adjoining parts of the main section 17 to define an acceptance passage 21 leading into an acceptance exit 22 in the bottom edge of the chute.

The principal part of the testing means includes an electromotive generator consisting of one pole piece or electrode in the form of a plate 23 of copper or other suitable metal, fixed within the chute passage above the runway 19 and having a horizontally extending runway ledge 24 on

which a coin element A may be moved, this runway ledge having a leading or forward edge portion 25, the purpose of which will hereinafter be explained, and a rearward or trailing edge portion 26 which terminates in space approximately above the acceptance opening 21 and the uppermost end of the runway 19 so that the coin A, in rolling off the upper horizontal edge 24, would tend to drop directly into the acceptance opening 21.

The electromotive generator is completed by the provision of a plate 27 of a metal different from the plate 23, preferably of carbon steel, mounted on horizontally spaced pins 28 extending in vertically elongated slots 29 formed in the plate 27 so that the latter may shift vertically. The second or carbon steel electrode or plate is provided with a wedge-shaped lower horizontal edge 30 (Figs. 3 and 5), which edge is normally maintained in approximate parallelism with the runway ledge 24 on the companion copper electrode or pole piece.

The upper or carbon steel plate or electrode 27 is urged downwardly by a bow spring 31. This bow spring 31 is disposed between the top edge of the electrode 27 and the facing provided by the intermediate cut-out plate 17 with the medial portion of the bow spring 31 bearing against the plate 17 and the free ends of the bow spring 31 positively urging the electrode 27 into a normally lowered and predetermined spaced relation relative to the companion electrode 23 and particularly the ledge portion 24 thereon.

The coin entrance 11 is disposed above the leading edge 25 of the runway 24 in such position that the coin A deposited therein tends to rest against the vertically spaced edge portions 32 of a U-shaped sliding pusher 33 (Figs. 2, 3, 4 and 5) mounted for horizontal sliding movement in horizontally extending, vertically spaced slots 34 (Fig. 2) formed in the face plate 16. The vertically spaced portions 32 on the pusher are situated so that the coin A will rest against both edge portions, as shown in Fig. 4, immediately following deposit, and during movement of the pusher 33 to the left until the coin drops off the left end 26 of the runway 24.

The pusher 33 is operatively connected to and reciprocated by the arm 15a having a pin and slot driving connection 15b with the same, as shown in Fig. 2. A spring 36 having one end suitably anchored and its opposite end connected to lever arm 15a, urges the latter and operating handle 12 associated therewith into a normal position in which the pusher is disposed, as shown in Fig. 4, ready to engage a coin. After depositing the coin, the patron turns the handle 12, shifting the pusher toward the left (Fig. 4) and pushing the coin A in between the electrodes 23 and 27 along the runway ledge 24, as indicated by the coin B. If the coin is of less than a predetermined diameter, the upper rim portion thereof obviously will not engage the edge 30 on the carbon steel electrode. The diameter of the opening 11 prevents the insertion of coins of greater than the required diameter.

The acceptance passageway 21 is normally closed by a blocking projection 40 (Figs. 2, 3a and 4) offset on an armature plate 41 pivotally mounted on and constituting part of an electricaly operated selecting device including a magnet 42 and spring means 43 (Fig. 3a) anchored to the magnet supporting frame and to the armature plate 41 and normally urging the armature plate 41 to dispose the latter at an angle with respect

to the plate 16 and to position the projection 40 in blocking position across the entrance of the passage 21 just opposite the upper edge portion 19a of the inclined runway 19. As a result of such normal positioning of the blocking portion 40, a coin leaving the end 26 of the upper runway ledge 24 will be prevented from entering the acceptance passage and roll over the runway 19 into the reject exit 20 unless the magnet 42 is energized to attract the armature plate counter-clockwise (Fig. 3) to retract the blocking portion 40 out of the acceptance passageway 21 before the coin reaches the latter.

The electrically operated selecting means 40—42 is adapted to be controlled by the electromotive generator 23—27 when a coin element having proper physical characteristics such as are found in an acceptable coin, for example a U. S. five-cent piece, is pushed between the electrodes 23 and 27 forming the electro-motive generator to develop an electro-motive force which operates certain electro-sensitive relay means which connects electro-motive force from an auxiliary source, such as a battery 51, with the coil 42 to effect withdrawal of the blocking projection 40 from the coin passage 21 which withdrawal of the projection 40 permits passage of the coin into the acceptance passage 21 and exit 22.

The current developed by the electro-motive generator is immediately utilized to operate a highly sensitive relay of the so-called galvanometer type which operates on relatively small currents. This relay is indicated as a unit at 45 (Figs. 2 and 3) mounted on the rear face plate 16, the relay having a moving coil system 46 including a movable contact 46a (Figs. 2, 3, 6); disposed by hair spring means 47 in a normally open circuit relationship with respect to a companion contact 48 (Figs. 2 and 6).

As shown in Fig. 6, one terminal of the moving coil 46 is connected by a conductor 49 to the electrode 27, the remaining terminal of the moving coil being connected by conductor 50 to the copper electrode 23, so that when the proper coin A is pushed between the electrodes an electro-motive force will be developed and current will be conducted through the moving coil system 46 to cause the latter to swing from its normal position and effect engagement of the moving contact 46a with the companion contact 48 to energize the coil 42 of the electrically operated selecting mechanism, in a manner now to be described.

An auxiliary work circuit having a source of electro-motive energy in the nature of a small dry cell type battery 51 is included as a part of the testing unit. This work circuit is made up by one terminal of the battery 51 being connected to one terminal of the coil 42, while the remaining coil terminal is connected via conductor 53 to one terminal 54 of a supervisory control switch 55 (Fig. 2) mounted on the rear panel 16 of the unit. A companion movable contact 56 of this supervisory switch 55 is connected in common with conductor 50 through the moving coil system 46 through the movable contact 46a thereof. The companion contact 48 of the movable contact 46a is connected by a conductor wire to the positive side of the battery 51.

The contact 56 of the supervisory switch is of the spring leaf variety and is normally biased into closed circuit engagement with the companion contact 54; however, contact 56 is held out of contacting engagement with contact 54 by engagement of an offset flange 15c on the

main operating arm with an insulated stud 57 on the contact 56, as shown in Fig. 2, so long as the operating arm 15a is in its normal position. As soon as the operating arm is turned out of normal position to move coin A between the electrodes, the supervisory switch contacts 54-56 will be closed; and as soon as the current from the electrodes causes the relay contact 46a to engage contact 48, the auxiliary work circuit from battery 51 will be completed and current will flow through the moving coil system 46 energizing the coil 42 which will attract the armature plate 41 and retract the blocking projection 40 so that the already moved coin A may drop into the acceptance passage 21, assuming the coin to be an acceptable one. As soon as the operator releases the handle 12, spring 36 will restore arm 15a to urge flange 15c against stud 57, thus opening the supervisory switch 55, deenergizing coil 42 and permitting the spring 43 to restore the selecting armature 41 and blocking projection 40 to normally effective position.

A mounting clip 60 (Fig. 2) is provided on wall 16 of the chute to support a small dry cell, there being terminals 61 and 62 engaging the terminals at the opposite ends of the battery for connection in the circuit of Fig. 6. Electrical connection to the electrodes of the electromotive generator is effected by a screw 63 (Fig. 2) threaded into a stud 64 (Figs. 4 and 5) on the copper plate electrode 23, while connection to the other carbon steel electrode is made to a projection 65 (Figs. 3 and 5) from the steel plate, which projection passes through the cover plate 16 just behind the galvanometer relay 45.

To summarize the operation of the device, it is assumed that the main operating arm 15a is in normal position and that a patron deposits coin A, of suitable diameter and characteristics intended to operate the device, in the opening 11, coin A resting against the edge portions 32 on the pusher. The patron turns the handle 12 and causes the pusher 33 to be displaced toward the left (Figs. 2, 4 and 5), thus pushing the coin A in between the copper electrode 23 and steel electrode 27, the latter yielding against spring means 31 to permit the ready passage of the coin while at the same time firmly urging the wedge-shaped edge portion 30 at the upper electrode into the rim of the coin to establish good electrical contact. Meanwhile, the supervisory switch 55 will have been closed so that the auxiliary battery circuit will be effective as soon as the galvanometer relay is actuated by current generated by the electromotive couple.

The metals employed for electrodes desirably occupy different positions in the electromotive series, and the current generated by the couple is dependent in part upon the metallic constituency of the coin element A as well as upon the pressure exerted upon the coin by the electrodes and the rate of movement of the coin between the electrodes. In order that variations in the rate of movement of the coin may not interfere with the operation of the device as a practical matter, the electro-sensitve device or galvanometer relay 45 is preferably chosen to be current-operated, as distinguished from voltage operated; and the electrodes are arranged and the electrical characteristics of the moving coil system 46 of the electro-sensitve device are chosen so that an acceptable coin, for example a five-cent coin of legitimate minting, will generate a certain average current in passing between the electrodes 23 and 27, which current will be suf-

ficient to operate the galvanometer relay, while other metallic coin elements will not generate the current requisite to displace the moving circuit of the galvanometer sufficiently to close circuits 46 and 48.

If the coin deposited is not an acceptable one, as aforesaid, the relay 45 will not operate and the blocking member 40 of the selecting device will remain in normal position and be struck by the coin after leaving the copper electrode runway 24 and pass on down the runway 19 into the reject exit 20. If the coin is such as will generate the requisite current to operate the relay 45, coil 42 will be energized to effect withdrawal of the blocking part 40 so that the coin may fall directly into passage 21 and pass through the acceptance exit 22. As soon as the operating lever 15a returns to normal position, the supervisory switch 55 will be automatically opened and the auxiliary battery circuit disconnected from the coil 42.

It will be obvious, as illustrated in Fig. 4, should a coin be deposited while the pusher 33 is in its coin advancing position, to the left, that upon the return of the pusher 33 to normal position such last deposited coin will be caused to drop through a by-pass 70 for gravitation through the reject exit 20 for return, by means not shown, to the depositor of such coin.

The various advantages and objects of the invention may be accomplished by modifications of the particular embodiment specifically described herein, and it is intended that the appended claims shall include all equivalent arrangements fairly coming within their call.

Having thus described our invention, what we claim as new and desire to protect by Letters Patent is:

1. In a coin testing device including a coin passage having an entrance and a reject exit and an acceptance exit, and testing means in the form of an electromotive generator comprising a pair of spaced electrodes disposed in said coin passage between the entrance and exits, one of said electrodes forming as supporting ledge for a coin inserted into said entrance opening, the other electrode being positioned above said first mentioned electrode and being normally urged in a direction toward the latter for engaging the peripheral edge of a coin passing therewith together with a control arm for effecting movement of such a coin between the electrodes whereby a coin so moved will be caused to gravitate toward said acceptance exit, the combination of a coin deflector normally disposed in said coin passage above said acceptance exit to cause a coin gravitating toward the latter to be deflected toward said reject exit, electrically operated means having a coil and an armature, said armature carrying the coin deflector and having spring means for urging the deflector into said normal position, a primary circuit adapted to utilize the electromotive force developed by said electrodes, a galvanoscope having the coil thereof arranged in said primary circuit with said electrodes and adapted to be energized when a coin having certain physical and electrical characteristics is passed between the electrodes as aforesaid, said galvanoscope including a normally open switch adapted to assume closed circuit condition when the coil thereof is energized as aforesaid, a secondary circuit, an auxiliary source of electrical energy for said secondary circuit, said switch and the coil of said electrically operated means arranged in said secondary circuit for withdraw-

ing said deflector out of said coin passage to permit coins to gravitate into said acceptance exit, and another switch in said secondary circuit actuated by said control arm when the latter is restored to a normal position for interrupting said secondary circuit thereby deenergizing the coil of said galvanoscope.

2. In a coin testing device, the combination of means providing a chute having an entrance and a plurality of exit passages, a control circuit, means providing an electro-motive generator for said control circuit adjacent said entrance, said generator including opposite electrode members between which a coin is adapted to be passed with opposite rim portions thereof each engaging one of said electrodes, means including a movable coin engaging member normally disposed to receive a coin from said entrance and for effecting movement of said coin between the electrodes as aforesaid, a relay including a coil connected in said control circuit and adapted to be energized by electricity developed by movement of said coin having certain physical and electrical characteristics, between the electrodes in the manner aforesaid, a work circuit for said coil for holding the latter energized under certain conditions, said relay including a switch means arranged in said work circuit and adapted to be disposed in circuit completing condition when said coil is energized as aforesaid, an auxiliary source of electricity for said work circuit, electrically operated selecting means for effecting movement of the coin toward a certain one of said exit passages as a result of movement of said coin relative to the electro-motive generator to develop the electricity as aforesaid, said selecting means comprising an armature having a ledge portion thereof normally disposed over one of said exit openings to direct coins to the other one of said exit openings and an electro-magnetic means arranged in said work circuit and adapted when energized to draw said ledge portion of said armature out of said normal position to permit coins to pass into said one of said exit openings, together with another switch in said work circuit for controlling the flow of current through the latter and coacting with said means for effecting movement of the coin between the electrodes, and to disconnect said auxiliary source of electricity from the relay coil and electromagnetic means when said moveable coin engaging member is in normal coin receiving position.

3. A coin testing device having, in combination, a coin chute provided with an entrance

and an acceptance and reject opening, a metal electrode arranged in said chute adjacent said entrance and providing an approximately horizontal runway on which the rim of a coin may move, said runway terminating in space above said acceptance and reject openings so that a coin will gravitate toward the acceptance opening, moveable blocking means normally blocking passage of a coin into said acceptance opening and directing a coin toward the reject opening, a second metal electrode arranged in said chute in spaced relation with respect to said first named electrode and provided with an edge portion adapted to engage the rim of a coin moving along said runway, a reciprocable pusher arranged on said chute for sliding movement between said electrodes, a crank arm arranged on said chute for swinging movement and having its free end linked to said pusher for moving the same from a normal position adjacent said entrance to engage a coin deposited in the latter and move said coin over and off said runway between the electrodes and develop thereby an electro-motive force, when coins having certain electrical and physical characteristics are deposited, an initial circuit embodying said electrodes to utilize the electro-motive force developed as aforesaid, relay means including a coil connected in said initial circuit and energized by current resulting from said electro-motive force when developed as aforesaid, and a work circuit for effecting operation of said moveable blocking means to withdraw the latter from blocking position over said acceptance opening, said work circuit including an electromagnet arranged adjacent said moveable blocking means and adapted when energized to attract the latter from normal blocking position, an auxiliary source of electrical energy, switch means operatively associated with said relay means and in the said work circuit and adapted to be closed upon energization of said coil as aforesaid, said work circuit also including said coil whereby to hold said switch in circuit completing condition, and another switch for said work circuit and normally disposed in circuit completing position and having one contact element thereof adapted to be engaged by said crank arm when the latter is in normal position to dispose said control switch in broken circuit position, and spring means connected to said crank arm and anchored to said chute for urging said crank arm into normal position.

WILLIAM PATZER.
WALTER A. TRATSCH.
